[57] CLAIM

The ornamental design for a drawer, as shown and described.

DESCRIPTION

FIG. 1 is a top plan view of a drawer showing our new design;

FIG. 2 is a side elevational view thereof on an enlarged scale, the opposite side being a mirror image thereof; FIG. 3 is a rear elevational view thereof on an enlarged scale;

FIG. 4 is a perspective view of a cross-section taken along lines 4—4 in FIG. 1 on an enlarged scale;

FIG. 5 is a partial cross-sectional view taken along lines 5—5 in FIG. 1 on an enlarged scale; and,

FIG. 6 is a front elevational view thereof.

The design is characterized by the particular parallel side panels in combination with the vertical back member and solid base panel, all as best illustrated in FIGS. 2 and 4.
